(57) **CLAIM**

The ornamental design for a cavity forming sleeve for post-tension concrete splicing device, as shown and described.

DESCRIPTION

FIG. 1 is a perspective view of a cavity forming sleeve for post-tension concrete splicing device with a top portion and a bottom portion joined;

FIG. 2 is a front elevational view thereof with the top portion and the bottom portion joined, and a rear elevational view is a mirror image of the front elevational view;

FIG. 3 is a left side view thereof with the top portion and the bottom portion joined, and a right side view is a mirror image of the left side view;

FIG. 4 is a top plan view thereof with the top portion and the bottom portion joined;

FIG. 5 is a bottom plan view thereof with the top portion and the bottom portion joined;

FIG. 6 is a perspective view thereof with the top portion and the bottom portion separated;

FIG. 7 is a front elevational view thereof with the top portion and the bottom portion separated, and a rear elevational view is a mirror image of the front elevational view;

FIG. 8 is a left side view thereof with the top portion and the bottom portion separated, and a right side view is a mirror image of the left side view;

FIG. 9 is a top plan view thereof with the top portion and the bottom portion separated; and,

FIG. 10 is a bottom plan view thereof with the top portion and the bottom portion separated.

The broken lines illustrate environmental subject matter only and form no part of the claimed design. Surface shading lines form no part of the claimed design.

1 Claim, 8 Drawing Sheets
